UNITED STATES PATENT OFFICE

ALEXANDER TAYLOR, OF REDLANDS, CALIFORNIA

SAFETY ENGINE STARTER

Application filed October 4, 1928. Serial No. 310,225.

This invention relates to cranking mechanism for internal combustion motors, and has for an object the provision of an improved mechanism for cranking internal combustion motors, this mechanism being of such a nature that it is adapted to disengage the crank from the crankshaft in the event of kicking back of the motor while being cranked, with a consequent decrease in the liability of injury to the operator. Hence, the present invention constitutes an improvement in the device of my co-pending application, Serial No. 272,747, filed April 25, 1928.

Another object of the present invention is the provision of means for positively ejecting the manually operable crank from that position in which it is engageable by a pawl to effect rotation of the crankshaft of the motor through the rotation of the crank. Hence, the device of the present invention is capable of operating more efficiently in positively preventing backward rotation of the crank when the crankshaft of the motor rotates backward as when the motor kicks back.

A further object is the provision of a starting mechanism of the general character described, which is particularly adapted for use in conjunction with internal combustion motors serving as prime movers for tractors and which is adapted to be installed upon tractors in the place of the ordinary cranks with which they are regularly equipped.

A still further object is the provision of a motor starting mechanism which is adapted to be installed upon vehicles, regardless of whether they are in process of manufacture or have been previously completed and placed in service.

It is a still further object of my invention to improve upon devices heretofore employed for the purposes stated, and to do so in such a way as to produce a starting mechanism which is simple and rugged in structure, relatively inexpensive to manufacture, and which is speedy and positive in operation.

The invention possesses other objects and advantageous features, some of which, with those enumerated, will be set forth in the following description of the invention's particular embodiment which is illustrated in the

drawings accompanying and forming a part of the specification.

Referring to the drawings:

Figure 1 is a top plan view of a starting mechanism embodying the principles of the present invention. The mechanism is shown coupled to the forward end of a conventional crankshaft.

Fig. 2 is a longitudinal, medial, vertical sectional view, the plane of section being indicated by the line 2—2 of Fig. 1 and the direction of view by the arrows. The operative parts of the device are shown in the positions assumed thereby when the crank is disengaged from the crankshaft.

Fig. 3 is a fragmentary view similar to Fig. 2, but showing the operative parts in the positions assumed thereby when the crank is coupled to the crankshaft as when manually starting the motor by turning the crank.

Fig. 4 is a transverse, vertical sectional view taken upon the line 4—4 of Fig. 3, with the direction of view indicated by the arrows.

Fig. 5 is a transverse, vertical sectional view taken upon the line 5—5 of Fig. 3, with the direction of view indicated by the arrows.

In terms of broad inclusion, the starting mechanism of the present invention comprises a stub shaft journalled in axial alignment with the crankshaft of an internal combustion motor. Means are provided for coupling the adjacent ends of the stub shaft and crankshaft, whereby the crankshaft may be rotated in a forward direction through the stub shaft to effect starting of the engine. A crank is journalled at the other end of the stub shaft in axial alignment therewith, and is capable of a limited degree of longitudinal movement in respect thereto. Means are provided for inter-locking the crankshaft and stub shaft for forward rotation together, and means are further provided for disengaging the interlocking means when the stub shaft rotates in a reverse direction, with the result that the crank is not similarly reverse-

ly rotated. In addition, further means are provided for moving the crank out of that position in which the inter-locking means may become effective, with the result that the op-

eration of the crank disengaging means is made more positive.

Specifically describing the invention in the most practical embodiment thereof of which I am at present aware, I have provided a housing 6 which is preferably in the form of half of the frustum of a cone. A disk 7 serves as a base for the housing 6, being secured thereto in any convenient manner such as by riveting; or, it may be cast integral therewith. Suitable means for attaching the housing 6 in operative position, are provided, such as a plurality of bolts 8 or their equivalent, extending through the base 7 into a portion 9 of the engine frame or other suitable supporting structure associated with the engine upon which the starting mechanism is to be installed. The housing 6 should be so disposed that an aperture 11 in the base 7 is in axial alignment with the crankshaft 12 of the motor. Moreover, the housing is preferably disposed so that the housing 6 extends forwards from the base 7 with its open side up. A journal 14 is provided at the outer end of the housing 6 within a journal-box 16, and a conventional journal-box cap 17 is held in position by nuts 18 threaded upon studs 19 extending through the cap 17 and threaded into the journal-box 16. A stud shaft 21 is revolutely disposed in the aperture 11 and is journaled adjacent its forward end in the journal 14. For this purpose the stub shaft is provided with cylindrical portions 22 and 23 respectively. Each of these cylindrical portions 22 and 23 is longer than the associated aperture 11 and journal 14 respectively, with the result that a limited degree of longitudinal movement of the stub shaft 21 is possible without displacement of the stub shaft 21 from its journals. An enlarged cylindrical portion 24 adjacent the cylindrical portion 22, and an enlarged square portion 26 adjacent the cylindrical portion 23, serve to limit this longitudinal movement.

Means for coupling the stub shaft 21 to the crankshaft 12 are provided in the form of a conventional crank ratchet 27, the inner face of which is provided with a plurality of inclined notches 28 within which a pin 29 rigid with the crankshaft 12 may be seated to effect forward rotation of the crankshaft 12 by turning the crank ratchet 27. Due to the inclination of the notches 28, as soon as the motor of which the crankshaft 12 is a part, starts, causing the crankshaft 12 to rotate forward faster than the crank ratchet 27, the pin 29 will slide upon the sloping surface 31 of the inclined notch 28 within which it is engaged, causing the crank ratchet 27 to be slid longitudinally of the crankshaft 12 and out of engagement with the pin 29.

The crank ratchet 27 is rigidly connected to the stub shaft 21 by means of a rod 32 upon one end of which the crank ratchet 27 is secured and upon the other end of which

threads 33 are formed to be engaged within complementary threads in an axial bore 34 in the inner end of the stub shaft 21.

A crank 36 is journaled within an axial bore 37 in the outer end of the stub shaft 21; and a flange 38 which is removably secured to the outer end of the stub shaft 21 by machine screws 39, is adapted to retain the shaft 41 of the crank 36 within the bore 37 by bearing against a shoulder 42 on the shaft 41 of the crank 36. The shaft 41 of the crank 36 is shorter than the bore 37 within which it is journaled, with the result that axial movement of the crank 36 in respect to the stub shaft 21 is possible, as well as rotary movement.

A ratchet and pawl connection between the shaft 41 of the crank 36 and the stub shaft 21 is provided in the form of a plurality of splines 43 upon the inner end of the shaft 41. A dog or pawl 44 is pivoted by means of a pivot pin 46 within the squared portion 26 of the stub shaft 21. The slot 48 in the squared portion within which the pawl 44 is mounted, extends inwards at right angles from one side 51 of the squared portion 26, and is positioned at one side of a plane perpendicular to the side 51 and passing through the center of the shaft 21. It is positioned upon that side of the plane which leads as the shaft 21 is rotating forwards, this direction being indicated by the arrows F on Figs. 4 and 5. The slot 48 extends into the bore 37 so that one corner 52 of the dog 44 is in position to engage the splines 43 and effect forward rotation of the stub shaft 21 when the shaft 41 of the crank 36 is rotated in a forward direction. However, being at one side of the center, the pawl 44 will be lifted from its spline-engaging position should the crank 36 be rotated in the opposite direction. This, of course, will also be the result if the stub shaft 21 should rotate in a forward direction faster than the shaft 41 of the crank 36.

From the structure thus far described, it is apparent that the motor may be started by means of the crank 36, by first sliding the stub shaft 21 inwards within its journals 9 and 14 until the crank ratchet 27 engages the pin 29 within certain of the notches 28. Then, by rotating the crank 36 in a clockwise direction, the leading side of one of the splines 43, will engage the side of the pawl 44 at its lowest corner 52, to effect similar rotation of the stub shaft 21. Since the stub shaft 21 is connected to the crankshaft 12 through the crank ratchet 27, the crankshaft 12 will also be rotated in the manner necessary to effect starting of the motor. When the motor starts, the forward rotation of the crankshaft 12 in respect to the crank ratchet 27, will cause the disconnection thereof by pushing the crank ratchet axially forward until the pin 29 disengages from the notches 130

28. The ratchet and spline connection between the shaft 41 and the stub shaft 21, serves to further prevent rotation of the crank 36 by the crankshaft 12, because should it so happen that the disconnection of the crank ratchet 27 from the crankshaft 12 should be so delayed to cause rapid forward rotation of the stub shaft 21, the bottom of the pawl 44 would be engaged by the trailing side of one of the splines 43, with the result that the pawl 44 would be swung upwards on its pivot 46 and disengage the crank 36 from the stub shaft 21. In other words, the pawl 44 normally connects the crank 36 to the stub shaft 21 so that the stub shaft 21 can not rotate backwards in respect to the crank 36, but which permits the stub shaft 21 to rotate forward in respect to the crank 36.

20 Means are provided for preventing re-engagement of the pawl 44 with the splines 43 after once being disengaged, until such engagement is intentionally carried out by the operator. A spring 53 is under compression 25 between the inner end of the shaft 41 of the crank 36 and the inner end of the bore 37 in the stub shaft 21. A plate or disk 54 is attached to the inner end of the shaft 41 in position to define the inner ends of the 30 grooves between the spline teeth 43. Obviously, this plate 54 holds the pawl 44 out of engagement with the spline teeth, except when the plate 54 is brought into register with a notch 55 in the bottom and side of the 35 pawl 44; and the spring 53 normally holds the shaft 41 and plate 54 at their outer extreme of movement so that the plate 54 is not in register with the notch 55.

Means are provided for automatically releasing the pawl 44 upon backward rotation 40 of the stub shaft 21 so that the crank 36 is not similarly reversely rotated. A ratchet gear 56 is mounted for rotary movement upon the cylindrical portion 24 of the stub shaft 45 21. This ratchet gear is provided with a plurality of teeth 57 which slope backwards and are engaged by a pawl 58 which is mounted for pivotal movement upon a pin 59 rigid with the plate 7. The connection between the 50 pawl 58 and teeth 57 is such that the ratchet gear 56 is permitted to rotate in a forward direction, but is prevented from rotating in a reverse direction. In order that the assembled stub shaft 21, crank 36, and ratchet gear 56 may be handled as a unit, I have found it desirable to provide a plate 61 fitting over the cylindrical portion 22 and against the shoulder terminating the cylindrical portion 24. This plate 61 is held in position by 55 preferably countersunk screws 62, and overlaps the cylindrical portion 24 so that the ratchet gear 56 is held against longitudinal displacement from the cylindrical portion 24.

The bore of the ratchet gear 56 is provided 60 with a plurality of ratchet teeth 63, the lead-

ing faces 64 of which are disposed substantially radially of the gear 56, and the trailing edges 66 of which are disposed substantially tangentially of the bore of the gear 56. A cam 67 is carried by the pawl 44 upon the 70 opposite side of the pin 46 from the portion 52 of the pawl which engages the splines 43. This cam 67 is urged outwards between two of the teeth 63 by a spring 68 under compression between the bottom of the pawl 44 and the bottom of the slot 48 in which it is mounted, so that when the stub shaft 21 rotates reversely in respect to the ratchet gear 56, the cam 67 will be depressed by the sloping surface 66 of one of the teeth 63, against the 80 action of the spring 68, resulting in the withdrawal of the pawl 44 from engagement with the spline 43. Consequently, the stub shaft 21 will be free to rotate without similarly rotating the crank 36. Furthermore, when the 85 pawl 44 is withdrawn from engagement with the spline 43, the plate 54 is simultaneously withdrawn from the slot 55, permitting the spring 53 to press the shaft 41 of the crank 36 axially outwards, with the result that it 90 will be impossible for the pawl 44 to reengage the spline 43 until the crank 36 is again intentionally pressed inwards by the operator.

To start an engine upon which the improved starting mechanism of the present invention is provided, the operator first presses the crank 36 inward until the plate 54 comes into register with the notch 55, whereupon the spring 68 will pivot the pawl 44 about the pin 46 until the corner 52 of the pawl engages one of the spline teeth 43 and the cam 67 is disposed between two of the ratchet teeth 63 in the ratchet gear 56. The engagement of the pawl 44 with the spline, 100 locks the stub shaft 21 to the crank for rotation thereby. Continued inward pressing of the crank 36 will result in sliding the stub shaft 21 inwards until the crank ratchet 27 is engaged upon the pin 29 of the crankshaft 12, as previously described. The motor may 105 now be started by turning the crank 36 in the well known manner.

The disengagement of the crank 36 from the crank shaft 12 after the motor starts, 110 either at the crank ratchet 27 or at the spline and pawl connection 43, 44, has already been described. Should it happen however, that the motor kicks back, i. e., causes the crank shaft 12 to rotate in a reverse direction, this 115 reverse rotation of the crank shaft will cause the stub shaft 21 to be similarly reversely rotated. The pawl 58 however, being in engagement with the teeth 57 of the ratchet gear 56, will prevent the ratchet gear 56 from 120 rotating in a reverse direction, whereupon the stub shaft 21 will rotate backwards in respect to the gear 56. This will bring one of the inclined faces 66 into engagement with the cam 67, causing the depression thereof against 125 130

the action of the spring 68, and the withdrawal of the pawl 44 from the spline 43, and also disengagement of the plate 54 from the notch 55, permitting the spring 53 to press the crank 36 forward in respect to the stub shaft 21, and permitting the stub shaft 21 to rotate freely without carrying with it the crank 36.

Various changes may be made in the details of the invention as herein described, without departing from the scope thereof as defined by the appended claims.

I claim:

1. A starting mechanism for an internal combustion engine having a crankshaft, said mechanism comprising a stub shaft engageable with said crankshaft, a crank journaled and mounted for longitudinal movement in axial alignment with said stub shaft, a plurality of spline teeth on said crank adjacent the inner end thereof, a plate secured to the inner end of said crank defining the inner ends of the grooves between said teeth, a pawl pivotally mounted on said stub shaft in position to engage the teeth of said spline, means urging said pawl into engagement with said spline, means urging the crank outwards from the stub shaft, said plate being adapted to engage within a slot in the pawl and hold the crank against longitudinal displacement when the pawl is engaged with the spline, and means operable when the crankshaft rotates in a reverse direction for withdrawing the pawl from engagement with the spline and plate.
2. A starting mechanism for an internal combustion engine having a crankshaft, said mechanism comprising a stub shaft engageable with said crankshaft, a crank journaled and mounted for longitudinal movement in axial alignment with said stub shaft, a plurality of spline teeth on said crank adjacent the inner end thereof, a plate secured to the inner end of said crank defining the inner ends of the grooves between said teeth, a pawl pivotally mounted on said stub shaft in position to engage the teeth of said spline, means urging said pawl into engagement with said spline, means urging the crank outwards from the stub shaft, said plate being adapted to engage within a slot in the pawl and hold the crank against longitudinal displacement when the pawl is engaged with the spline, a ratchet gear mounted for rotary movement upon said stub shaft, a plurality of teeth on the bore of said ratchet gear, the trailing face of each of said teeth being arranged substantially tangentially to the bore of the gear, a cam on said pawl in engagement with said ratchet gear teeth to effect removal of said pawl from engagement with said spline when the stub shaft rotates backward within said ratchet gear, and a second pawl associated with said ratchet gear to hold it against backward rotation.
3. A starting mechanism for an internal combustion engine having a crankshaft, said mechanism comprising a stub shaft engageable with said crankshaft, a crank journaled and mounted for longitudinal movement in axial alignment with said stub shaft, a plu-

rality of spline teeth on said crank adjacent the inner end thereof, a plate secured to the inner end of said crank defining the inner ends of the grooves between said teeth, a pawl pivotally mounted on said stub shaft in position to engage the teeth of said spline, means urging said pawl into engagement with said spline, means urging the crank outwards from the stub shaft, said plate being adapted to engage within a slot in the pawl and hold the crank against longitudinal displacement when the pawl is engaged with the spline, a ratchet gear mounted for rotary movement upon said stub shaft, an eccentric portion of said gear adapted to engage said pawl and move it to spline-disengaging position upon backward rotation of said stub shaft within the ratchet gear, and a second pawl associated with said ratchet gear to hold it against backward rotation.

4. A starting mechanism for an internal combustion engine having a crankshaft, said mechanism comprising a stub shaft engageable with said crankshaft, a crank journaled and mounted for longitudinal movement in axial alignment with said stub shaft, a plurality of spline teeth on said crank adjacent the inner end thereof, a plate secured to the inner end of said crank defining the inner ends of the grooves between said teeth, a pawl pivotally mounted on said stub shaft in position to engage the teeth of said spline, means urging said pawl into engagement with said spline, means urging the crank outwards from the stub shaft, said plate being adapted to engage within a slot in the pawl and hold the crank against longitudinal displacement when the pawl is engaged with the spline, a ratchet gear mounted for rotary movement upon said stub shaft, a plurality of teeth on the bore of said ratchet gear, the trailing face of each of said teeth being arranged substantially tangentially to the bore of the gear, a cam on said pawl in engagement with said ratchet gear teeth to effect removal of said pawl from engagement with said spline when the stub shaft rotates backward within said ratchet gear, and a second pawl associated with said ratchet gear to hold it against backward rotation.

5. In a cranking mechanism, a pair of revolvably mounted and axially aligned shafts, a series of teeth on one of said shafts, a pawl pivotally mounted on the other shaft and engageable with said teeth to lock the shafts together for rotation in one direction, means for withdrawing said pawl from tooth-engaging position upon reverse rotation of the shafts, and a projection on said toothed shaft engageable with said pawl to hold the pawl out of engaging position, said toothed shaft being movable to release the pawl from the projection.

6. In a cranking mechanism, a pair of revolvably mounted and axially aligned shafts, a

series of teeth on one of said shafts, a pawl pivotally mounted on the other shaft and engageable with said teeth to lock the shafts together for rotation in one direction, said pawl being offset from the axis of the shafts to permit unrestricted reverse rotation of one shaft in respect to the other, means for withdrawing said pawl from tooth-engaging position upon reverse rotation of the shafts, and a projection on said toothed shaft engageable with said pawl to hold the pawl out of engaging position, said toothed shaft being movable to release the pawl from the projection.

7. In a cranking mechanism, a driving shaft and a driven shaft revolvably mounted and axially aligned, said driving shaft being axially slidable in respect to the other shaft, teeth on one of said shafts, a pawl on the other shaft, a spring urging said pawl into engagement with said teeth to lock the shafts together for rotation in one direction, means for withdrawing said pawl upon reverse rotation of said driven shaft, and a spring urging said driving shaft out of that position in which the pawl is engageable with the teeth.

8. In a cranking mechanism, a driving shaft and a driven shaft revolvably mounted and axially aligned, said driving shaft being axially slidably in respect to the other shaft, teeth on one of said shafts, a pawl on the other shaft, a spring urging said pawl into engagement with said teeth to lock the shafts together for rotation in one direction, a projection on said toothed shaft receivable within a notch in said pawl when the pawl is in tooth-engaging position, means for withdrawing said pawl upon reverse rotation of said driven shaft, and a spring urging said driving shaft out of that position in which the projection is in register with said notch.

In testimony whereof I have signed my name to this specification.

ALEXANDER TAYLOR.
